UNITED STATES PATENT OFFICE.

LEO STEIN, OF NEW YORK, N. Y., AND WILLIAM A. SPARKS, OF HOBOKEN, NEW JERSEY, ASSIGNORS TO THE NATIONAL CASKET COMPANY, OF HOBOKEN, NEW JERSEY.

DESIGN FOR A TOP FOR BURIAL-CASKETS.

SPECIFICATION forming part of Design No. 28,148, dated January 11, 1898.

Application filed November 17, 1897. Serial No. 658,872. Term of patent 7 years.

To all whom it may concern:

Be it known that we, LEO STEIN, residing at New York, in the county and State of New York, and WILLIAM A. SPARKS, residing at Hoboken, in the county of Hudson and State of New Jersey, citizens of the United States, have invented and produced a new and original Design for a Top for Burial-Caskets, of which the following is a specification, reference being had to the accompanying drawings, forming part thereof.

Figure 1 is a plan view of a casket-top, showing our new design. Fig. 2 is an isometric view of an end of the aforesaid top, and Fig. 3 is a sectional view taken on the line 3 3 of Fig. 1.

The leading or material feature of our design consists of ornamental columns *a*, disposed or arranged at the corners of the casket-top, as shown in Fig. 1. Said columns *a* are

substantially curvilinear in profile and extend upwardly from substantially the base of the casket-top to the panel-molding *b*, near the upper part of said top, as shown in Figs. 2 and 3.

Having described our invention, what we claim as new, and desire to secure by Letters Patent, is—

The design for a top for burial-caskets, substantially as herein shown and described. 30

In testimony whereof we have hereunto signed our names, in the presence of two attesting witnesses, at the city of Hoboken, in the county of Hudson, in the State of New Jersey, this 16th day of October, 1897.

LEO STEIN.
WILLIAM A. SPARKS.
